THEFT ALARM SWITCH

Joseph F. Huss, Charlotte, N. C., assignor of one-half to Burman K. Bialock, Charlotte, N. C.

Application April 20, 1936, Serial No. 75,450

1 Claim. (Cl. 200—4)

This invention relates to theft alarms, and is an improvement over the construction embodied in my Patent No. 2,000,136 which issued May 7, 1935.

5 In the construction embodied in my prior patent there were incorporated a number of solenoids which actuated a circuit making and breaking means, and it is in order to eliminate the use of the solenoids that the hereinafter described 10 invention was conceived and designed. This invention has for an important object thereof the provision of a manually operable circuit making and breaking means which may be used in motor vehicles or buildings of various types so as to 15 make or break the main electric circuits and to make or break one or more signal circuits, and in the case of buildings to, at the same time the signal circuits are closed, also close a night light circuit, as in the case of stores or like establishments 20 where a night light is left burning in the vicinity of a safe.

Another object of this invention is the provision of a compound switch for making and breaking a plurality of electric circuits, the switch being so constructed that it may be operated from a remote point, so that in the case of motor vehicles the switch may be positioned in a concealed place, as beneath a hood which is capable of being locked, the operating means for the 30 switch being such as to permit the use of a suitable locking means to permit the positioning of the operating means on the dashboard of the vehicle.

A further object of this invention is to provide 35 a switch construction which may be interposed in a plurality of electric circuits, the switch being of such a simple construction as to permit the manufacture and sale of the switch at a very low cost.

40 With the foregoing and other objects in view, the invention will be more fully described hereinafter, and will be more particularly pointed out in the claim appended hereto.

In the drawings, wherein like symbols refer to 45 like or corresponding parts throughout the several views,

Figure 1 is a perspective view of a switch constructed according to an embodiment of this invention, the switch being shown interposed in a 50 plurality of electric circuits which are shown in diagrammatic form.

Figure 2 is a sectional view taken on the line 2—2 of Fig. 1.

Figure 3 is a view similar to Fig. 2 but showing 55 the light circuit contacts in closed position.

Figure 4 is a perspective view of a modified form of this switch designed for use with building circuits, and showing the switch interposed in a plurality of electric circuits which are shown in diagrammatic form.

5 Referring to the drawings, and first to Figs. 1, 2 and 3, the numeral 10 designates a base of suitable construction, and preferably of insulating material, which is provided with a pair of uprights or posts 12 and 13, one adjacent each end 10 of the base.

A rod or slide member 11 is slidably carried by the uprights or posts 12 and 13 at a point spaced upwardly from the top of the base 10, and an insulated body 14 is secured to the rod 11 between the uprights or posts 12 and 13, and this body 14 is shorter in length than the distance between the uprights or posts 12 and 13 so that the rod 11 with the body 14 secured thereto may have sliding movement with respect to the supports 12 and 13.

The base 10 is adapted to be positioned beneath the hood of a motor vehicle which is capable of being locked or in some other suitable concealed place. A pair of main contacts 15 and 16 25 are secured to the base 10 and are adapted to wipe the insulated body. The contact 15 is adapted to be secured as by a conductor 17 to one side of a battery or other source of electric current supply 18, and the other side of the battery 18 is adapted to be grounded to the frame 30 of the vehicle in the usual manner. A bridging member 19 is secured to the insulated body 14, and is adapted in one position of the slide, comprising the rod 11 and the body 14, to engage 35 between the contacts 15 and 16 and in another position of the slide to be disposed in spaced relation to the contacts 15 and 16 to break the circuit in which the contacts or wipers 15 and 16 are interposed.

40 A conductor 20 is connected at one end to the contact 16 and at the other end to an ammeter "A" of usual construction and here shown diagrammatically. A conductor 21 leads from the ammeter "A" to a starter motor switch 22, the 45 starter motor "M" being connected at one side to the conductor 21 and at the other side being connected to the ground.

A conductor 23 is connected at one end to the conductor 21 and at the other end to a terminal 50 24 constituting a part of an ignition switch, generally designated as 25. This switch 25 comprises a substantially Y-shaped member 26 which is pivoted as at 27 to a suitable base (not shown), and the stem portion of this Y-shaped member 55

26 is adapted to wipe the fixed terminal or contact 24. One arm 28 of the switch 25 is adapted to engage a terminal 29 when the switch 25 is in a position to close the ignition circuit, and 5 the other arm 30 of the Y-shaped member 26 is adapted, when the ignition circuit is opened to engage a terminal or contact 31. A conductor 32 is connected at one end to the terminal 31, and at the other end is connected to a yieldable contact or wiper 33 which is secured to the base 10 in a position for engagement with the rod 11 which is preferably a metal rod.

10 A second yieldable contact 34 is secured to the base 10 in opposed relation to the contact or 15 wiper 33, and a conductor 35 is connected at one end to the contact 34 and at the other end to the ground. Preferably a signal light 36 is 20 interposed in the conductor 35 so that in one position of the slide, that is when the rod 11 is disposed between the confronting ends of the 25 contacts 33 and 34, which is the vehicle running position of the slide, this signal light circuit is adapted to be closed provided the ignition switch 25 is moved to break the ignition circuit and 30 complete the circuit from the conductor 23, through the terminal 24, arm 30 and terminal 31 to the conductor 32. In Figure 1 the slide is shown in the signal operating position, and in this position the ends of at least one of the 35 contacts 33 and 34 are disposed in spaced relation to the adjacent end of the rod 11 so that the circuit in which the light 36 is interposed will be broken.

This signal light 36 is designed for the purpose of indicating to the operator of the vehicle 40 whether or not the ignition switch is turned on when the slide 11-14 is in a vehicle running position. More particularly the signal light 36 is 45 designed for the purpose of indicating, when it is lighted that the motor is stopped so that it will be safe for an attendant to place gasoline in the tank of the vehicle, it being understood that many of the gasoline engines at present available are so designed that the operator cannot 50 determine from any physical condition with respect to the vehicle, aside from operating the clutch, whether or not the engine is running. When the ignition switch 25 is in its "off" position, the engine indicating signal 36 will be 55 lighted at all times, it being understood that at this time the slide 11-14 is in a vehicle running position.

A pair of alarm signal contacts 37 and 38 are 60 secured to the base 10, one on each side of the slide 14 in wiping contact therewith, and a bridging member 39 is carried by the slide member 14 and is adapted in one position of the slide member 14 to bridge the two contacts 37 and 38. The contact 37 is connected to the conductor 47, in this instance through connection with the contact 15, and the contact 38 has one end of a conductor 40 connected thereto, the opposite end of the conductor 40 being connected to a signal 41 which may be of either a sound producing type or any other character of signal. The conductor 40, through the contacts 38, 37, 45, and the conductor 47, connects the signal 41 to one side of the battery 18. The other or ground side of the battery 18 is connected to the signal 41 by means of a conductor 42, which is connected to the signal 41 and to a contact 43 secured to the base 10.

In the signal operating position of the slide 50 47, which position is shown in Fig. 1, the contact 43 wipes the bridging member 19. A con-

tact 44 is also secured to the base 10, and in the present instance engages the top of the slide 14, and is adapted to wipe the bridging member 19. The contact 44 is connected, as by a conductor 45, to one side of an alarm switch 46 which is biased by a spring 47 to a closed position. The other side of the switch 46 is connected as by a conductor 48 to the frame of the vehicle to thereby complete the circuit from the battery 18 to the signal 41. The complete signal 10 circuit is as follows: Starting from one side of the battery 18 through conductor 47, contacts 15-37, bridging member 39, contact 38, conductor 40, signal 41, conductor 42, contact 43, bridging member 19, contact 44, conductor 45, 15 switch 46, and conductor 48 to the ground or opposite side of the battery.

The compound switch here disclosed is also adapted to control the operation of the light circuit of the vehicle, and in order to do this, a 20 conductor 49 leads to a contact 50 carried by the base 10, and a switch 51 is interposed in this conductor 49. This switch 51 is a conventional light switch of the manually operated type. A contact 52 is secured to the base 10 and 25 in the present instance this contact 52 is of the yieldable type, being biased to closed position. Preferably the adjacent end of the slide 14 is slightly tapered, as at 53, so that when the slide 14 is moved to signal operating position the 30 tapered end of the slide 14 will spread the contact 52 apart from the contact 50, and when the slide 14 is in a vehicle running position the two contacts 50 and 52 will be in contacting 35 position, these two positions being more clearly shown in Figs. 2 and 3.

The conductor 49 is connected to the conductor 21 at one side of the ammeter "A", and the contact 52 is connected as by a conductor 54 to one side of the lights 55, the other side of the 40 lights 55 being connected to the ground.

A slide operating lever 56 is mounted on a shaft 57 carrying a knob 58, and the lever 56 is connected to the slide rod 11 by means of a link or connecting rod 59. The knob 58 and the shaft 45 57 may have a locking means associated therewith in order to prevent unauthorized movement of the slide 11-14. It will be understood that there may be as many switches 46 as are considered necessary or desirable, and that these 50 switches 46 are held in open position by the normal position of the parts associated therewith. In other words, the switch 46 may be positioned on the body of the vehicle in a position where it will be held in open position when the hood is closed, and when the hood is opened the spring 47 will close the switch. The switch 46 may also be 55 associated with the windows, doors, spare tire, gas tank cap or any other displaceable part of the vehicle, so that once the slide 11-14 has been set by rocking of the lever 56 to signal operating position no displaceable part of the vehicle having a signal switch 46 associated therewith may be moved without closing the electric circuit to the signal 41.

In Figure 4 there is shown a compound switch of the type shown in Figure 1 which is adapted to be connected to the lighting circuits of buildings. In this form the electric circuits are shown diagrammatically and the source of current supply 70 is shown as a battery, this being merely for illustrative purposes to show the complete circuits.

A base 10' has a pair of uprights 12' and 13' secured thereto, and a slide comprising a rod 11' and 14' is slidably carried by the uprights 12' 75

and 13'. A pair of contacts 15' and 16' are secured to the base 10', the contact 15' being connected to the source of current supply 18' by a conductor 17'. A bridging member 19' is secured to the slide 14' and in one position of the slide this member 19' is adapted to bridge the contacts 15' and 16', as shown in Fig. 4. A conductor 20' is connected to the contact 16' and this conductor 20' has lights 59 connected thereto and also has a main light switch 60 interposed therein. The conductor 20' is connected to a return conductor 61 which is connected to a ground terminal 62 carried by the base 10'.

A pair of contacts 33' and 34' are secured to the base 10', and in this instance the contact 34' is directly connected to the contact 15'. A night light 36' is connected as by a conductor 35' to the contact 33', and one end of the conductor 35' is connected to the return conductor 61 through the conductor 20'. A bridging contact 62 is carried by the slide member 14', and in the signal operating position of the slide 14' the bridging contact 62 is adapted to be wiped by the contacts 33' and 34' so as to maintain the night light 36' lighted when the main lighting circuit 20'-61 is cut off by movement of the bridging contact 19' from between the two contacts 15' and 16'.

A pair of signal contacts 37' and 38' are mounted on the base 10', the contact 37' being connected directly to the contact 15'. A conductor 40' is connected to the contact 38', and a signal 41' is interposed in this conductor 40' and is connected to one side of a signal switch 46' which is biased to closed position by a spring 47'. The other side of the switch 46' is connected as by a conductor 48' to the return conductor 61. A bridging member 63 is carried by the slide 14', and in the signal operating position of this slide the bridging member 63 is adapted to connect the contacts 37' and 38'. An operating knob 58' is secured in this instance directly to one end of the rod 11', although it will of course be understood that the rod 11' may be operated from a remote position if desired in a manner somewhat similar to the operation of the rod 11.

In the use and operation of the switch construction shown in Fig. 1, when it is desired to operate the vehicle in the normal manner, the slide 11-14 is moved, in this instance to the right as viewed in Fig. 1, to a vehicle operating position with the bridging member connecting the contacts 15 and 16 together. In vehicle operating position the bridging member 39 will be disposed away from the contact 37, thus breaking the circuit to the alarm 41, and the bridging member 19 will be out of engagement with the contact 44, so that any displaceable part of the vehicle associated with a signal switch 46 may be moved without operating the signal 41. Now assuming that the ignition switch 25 is closed and the operator of the vehicle desires to have gasoline placed in the tank, turning off of the ignition switch 25 will close the circuit from conductor 20, 23, terminal 24, switch arm 30, 65 to terminal 31 and conductor 32. The rod 11 will bridge the space between the contacts 33 and 34 so that the completed circuit will be made through conductor 35, bulb 36, ground or frame of the vehicle, and thence to the battery 18. A contact 64 is connected to contact 16, and is adapted to maintain contact with the bridging member 19 so that movement of the starter switch 22 to closed position will operate the signal 41 through the circuit comprising the conductor 20, 70 starter switch 22, ground, battery 18, con-

ductor 17, contact 37, bridging member 39, contact 38 and conductor 40.

In the vehicle operating position of the slide 11-14, the contacts 50-52 will engage each other so that the light switch 51 may be closed 5 to effect a closing of the lighting circuit of the vehicle.

When the operator of the vehicle desires to lock the vehicle, the ignition switch 25 may be moved to open position, initially lighting the bulb 36 10 as indicated hereinbefore. The knob 58 is then turned to move the slide 11-14 to signal operating position which is the position shown in Fig. 1. In this position the lighting circuit is broken by movement of the contacts 50-52 to 15 the position shown in Fig. 2 so that the lights of the vehicle cannot be operated. In the event the displaceable part of the vehicle associated with the spring-pressed signal switch 46 is displaced the signal 41 will be actuated, the circuit 20 being from the ground to one side of the battery 18, conductor 17, contact 37, bridging member 39, contact 38, conductor 40, signal 41, conductor 42, contact 43, bridging member 19, contact 44, conductor 45, switch 46, and conductor 48 to the 25 ground.

The signal switch shown in Fig. 4 operates in a manner similar to the switch shown in Fig. 1, the normal lighting position of the switch being the position shown in this figure, where the source 30 of current supply 18' is connected to the switch 60 through the conductor 17', contact 15', bridging member 19', contact 16' and conductor 20'. In this lighting position of the switch the circuit is broken to the night light 36' and also to 35 the signal circuit including the conductor 40'.

In most stores or other establishments it is the practice to maintain at least one night light in fairly close proximity to the safe, cash register or like repository for money, and it is for this 40 purpose that the night light 36' is provided which will be in a closed circuit including the contacts 34', 33', conductor 35', and conductor 61, when the slide has been moved to signal operating position in which position the bridging contact 62a 45 will engage between the contacts 33'-34' and thus maintain the night light circuit closed.

When the slide 11'-14' is moved to the left as shown in Fig. 4, the bridging contact 63 will be disposed between the signal contacts 37'-38', 50 so that the parts of the building, such as doors, windows or other displaceable parts, associated with the signal switch 46' will upon displacement thereof permit the spring 47' to effect a closing of the signal circuit through the conductor 40', 55 signal 41', switch 46' to the return lead or conductor 61. The signal 41' may be either a visible or an audible signal, and as shown there may be a number of these signals, one remote from another which will be actuated by closing of the 60 switch 46'.

It will be obvious that various changes in the construction, combination and arrangement of parts could be made, which could be used without departing from the spirit of my invention, 65 and I do not mean to limit the invention to such details, except as particularly pointed out in the claim.

Having thus described my invention, what I claim and desire to secure by Letters Patent of 70 the United States is:—

A circuit make and break device comprising a base, a shiftable element slidably mounted on said base and having spaced circuit making and circuit breaking sections, a pair of spring con- 75

tacts mounted on the base adjacent one end of said element, said one end of the element having a reduced portion whereby the element may be shifted to one position to place the reduced portion between said contacts to allow them to engage and to a second position to place a circuit breaking section between said contacts, a plurality of contacts mounted on the base to engage said element on substantially the same circumference whereby said element is adapted in said one position to place a circuit breaking section in engagement with said contacts to open the circuit through them and in said second position to place a circuit making section in engagement with said contacts, a further pair of contacts mounted on the base for engagement with opposite sides of the element and adapted to be connected by a circuit making section in said one position of the element and to be disconnected by a circuit breaking section in said second position of the element, a connector between one of the further pair of contacts and one of said plu-

rality of contacts to interconnect the last mentioned sets of contacts when the said element is shifted to the second position, an additional pair of contacts mounted on said base for engagement with said element adapted to be connected by a circuit making section when the element is in said second position and to be disconnected when the element is in said one position, a second connector between one of said additional pair of contacts and the other of said further pair of contacts to interconnect the named sets of contacts when the element is in said second position, a pair of spring contacts mounted in spaced relation on the base at one end of said element so that in said one position the tip of the element engages both of them, said tip being of conducting material to make the circuit between said contacts in said one position of the element, in the second position of said element said tip being withdrawn from said contacts to break the circuit between them.

JOSEPH F. HUSS.
